UNITED STATES PATENT OFFICE.

WILLIAM C. FARNUM, OF ARLINGTON, VERMONT, ASSIGNOR TO UNION TYPEWRITER COMPANY, OF JERSEY CITY, NEW JERSEY, A CORPORATION OF NEW JERSEY.

TYPE-WRITING MACHINE.

SPECIFICATION forming part of Letters Patent No. 732,533, dated June 30, 1903.

Application filed November 20, 1901. Serial No. 83,012. (No model.)

To all whom it may concern:

Be it known that I, WILLIAM C. FARNUM, a citizen of the United States, and a resident of Arlington, in the county of Bennington and 5 State of Vermont, have invented certain new and useful Improvements in Type-Writing Machines, of which the following is a specification.

My present invention relates to what may 10 be termed "auxiliary platen-feed mechanism for type-writing machines" and by means of which the platen may be rotated in either direction to any extent independently of the ordinary line-spacing mechanism to bring any 15 desired portion of the paper to the printing-line. The auxiliary platen-feed mechanism is particularly available for irregular line-spacing or for filling in partly-printed blanks.

The object of my invention is to provide a 20 simple and efficient device of the character described.

To the above and other ends, which will hereinafter appear, the invention consists in the novel arrangement and combination of 25 parts hereinafter described, and particularly pointed out in the claims.

In the accompanying drawings, wherein like reference characters indicate corresponding parts in the various views, Figure 1 is a topview 30 of a platen and platen-frame, showing the application of the device which constitutes the subject-matter of my invention. Fig. 2 is a fragmentary longitudinal sectional view of a portion of the same, the section being taken 35 on the line *y y* of Fig. 3 and looking in the direction of the arrow in said figure. Fig. 3 is an end view of the same looking toward the right-hand end of the platen. Fig. 4 is an end view of the parts represented in Fig. 1 with 40 portions thereof in section, the section being taken on the line *x x* of Fig. 2 and looking in the direction of the arrow in said figure.

In the drawings a sufficient number of parts of a type-writing machine is illustrated 45 to show my invention, the platen and platen-frame shown being those of a No. 6 Remington type-writing machine.

The platen-frame 1 has a platen 2 mounted to rotate therein, and this platen may be provided with the usual finger-wheel at the left-

hand end thereof. The platen is secured to the platen-shaft 3 in any suitable manner, and the right-hand end of the platen-shaft 3 extends beyond the platen-frame 1 and is provided with a collar 4, that is adapted to prevent a longitudinal movement in one direction of a line-spacing wheel 5 on the shaft. This line-spacing wheel is adapted to revolve independently of the shaft and is provided with the usual ratchet-teeth 6 on the periphery thereof, and a laterally-extending crown bevel-gear 7 projects from the outer face of the ratchet-wheel, and a hollow finger-wheel 8 is connected thereto by a screw 9. The ratchet-wheel 5 likewise carries a cylindrical collar or abutment 10, which is adapted to contact with a gear-wheel 11, that is secured to the platen-shaft 3 by a screw 12, that projects through the flange 13 on the gear and bears at its inner end upon the platen-shaft. A finger-wheel 14 is 55 mounted loosely upon the platen-shaft and carries a laterally-extending headed pin or stud 15, that constitutes the shaft upon which a bevel-pinion 16 revolves, the head of the pin preventing the displacement of the pinion 60 65 from the shaft. The right-hand end of the shaft 3 is headed at 17, and interposed between this head 17 and the finger-wheel 14 is a spring-washer 18, the flexion of which exerts a pressure between the finger-wheel 14 70 and the head 17 of the shaft, thus tending to force the finger-wheel in the direction of the arrow in Fig. 2, thereby maintaining a close engagement between the teeth of the bevel-pinion 15 and the bevel-teeth 19 and 20 of the 75 80 85 concentric gears 7 and 11. By these means lost motion or backlash between the gears is prevented. The head 17 is preferably formed of a screw, the stem of which is received in a threaded opening in the end of the shaft and which enables the parts carried on the right-hand end of the platen-shaft to be assembled 90 thereon. It will be observed that the single bevel-pinion 16 co-operates with the teeth 19 and 20 on the two gears 7 and 11, respectively. 95

A line-spacing pawl 21 co-operates with the teeth of the line-spacing wheel, and this pawl is pivoted at 22 to one arm 23 of a two-arm spacing-lever. The other arm 24 of this spacing-lever is provided with a finger-piece 25, by 100

means of which it can be vibrated on its pivot 26, by which it is connected to the platen-frame 1. The line-spacing lever is restored to the normal position by a spring 27, which 5 bears at one end against a pin 28, projecting from the platen-frame, and at its opposite end against a pin 29, secured to the arm 23 of the spacing-lever. The spacing-pawl 21 is provided with a depending arm 30, that is adapted 10 to bear when the parts are in the normal position (represented in Fig. 4) against any one of the three faces 31 of the controlling-piece 32, which is pivoted at 33 to the platen-frame. This controlling-piece 32 limits the 15 return movement of the line-spacing pawl and lever, and thus controls the throw thereof, so as to feed the distance of one, two, or three teeth of the ratchet-wheel in accordance with the adjustment of the controlling-piece 20 around its pivot 33. It will be understood that suitable means are provided to retain the controlling-piece in any one of the three positions to which it may be adjusted. The forward movement of the depending arm 30 25 of the line-spacing pawl is limited with relation to the arm 23 by a laterally-projecting stop-pin 34. The arm 23 of the line-spacing lever is likewise provided with a rigid locking pawl or dog 35, which is adapted to be forced 30 into contact with the teeth 6 of the line-spacing wheel when the line-spacing pawl has reached the limit of its movement, and thus prevent a rotation of the line-spacing wheel in either direction. 35 Coöoperating with the peripheral teeth on the line-spacing wheel 5 is a detent-roller 36, carried by a spring 37, that is secured at 38 to the platen-frame and which presses the roller against the teeth. This spring-pressed 40 roller 36 tends to maintain the line-spacing wheel against accidental displacement and assures an accurate positioning of the platen at regular line-space distances when the ordinary line-space mechanism just described is 45 operated.

In the operation of the device for ordinary line-spacing a rotation will be given to the line-spacing wheel 5 by the spacing-lever, and a corresponding rotation will be transmitted 50 to the platen 2 by reason of the fact that the various gears are in mesh, and the bevel-pinion 16 will revolve bodily with the coöperating gears and with the finger-wheel 8. Should, however, the operator desire to provide a differential spacing—that is to say, to 55 provide a rotating movement of the platen which differs from that which may be attained with the line-spacing wheel 5—it is merely necessary to rotate the finger-wheel 14, which will cause the pinion 16 to be carried 60 around with it. The pinion 16, meshing as it does with the teeth of the gear 11, which is fixed to the platen-shaft, will cause the bevel-pinion to be rotated, thus transmitting movement 65 to the crown-gear 7, with which the pinion likewise meshes. The gear-wheels 7

and 11 being of different size and the pinion 16 being beveled will provide a differential movement of the gears 7 and 11. It should be understood that the gear 11 is preferably 70 provided with a greater number of teeth than the gear 7. Thus we will assume that the gear 11 has thirty-two teeth, whereas the crown-gear 7 has but thirty-one. It will follow, therefore, that a rotation of the finger-wheel 75 14 will cause a relative movement between the line-spacing wheel 5 and the platen 2, or, in other words, if the line-spacing wheel be maintained against movement and the finger-wheel 14 is rotated it will effect a turning of 80 the platen. The detent-roller 36 maintains the line-spacing ratchet-wheel 5 fixed against rotation when the finger-wheel 14 is rotated, the tension of the spring 37 being sufficient for this purpose. 85

The finger-wheel 8, however, is at all times effective to move the line-spacing wheel and the platen together, all of the parts at this time being moved bodily, as in the case when the line-spacing wheel itself is operated by 90 its coöperating pawl 21.

It will be observed that the auxiliary platen-feed mechanism in addition to its employment as a means for bringing any desired point on the paper to the printing-line is also 95 available as a means for distributing the wear on the platen—that is to say, it may be used to change the relative position of the line-spacing wheel and the platen, so that the points of impact between the type and the 100 platen may be changed and the wear distributed over the entire surface of the platen instead of upon fixed lines, as is ordinarily the case where the line-spacing mechanism alone is employed. 105

While I have shown the bevel-pinion 16 as a single pinion, it is obvious that two such pinions may be employed, one coöperating with each of the gears 7 and 11, and that suitable connection may be made between the 110 separate bevel-pinions and various other changes may be made in the construction and operation of the device without departing from the spirit of my invention.

What I claim as new, and desire to secure 115 by Letters Patent, is—

1. In a type-writing machine, the combination of a platen, a line-spacing wheel, a gear-wheel which is supported and carried by said spacing-wheel, a finger-wheel carried by said gear-wheel for rotating the platen and spacing-wheel together, a gear-wheel connected to the platen, a regulating finger-wheel, and a gear-wheel carried thereby and adapted to co-operate with the other gear-wheels to effect a 120 movement of the platen relatively to the line-spacing wheel when the regulating finger-wheel is turned. 125

2. In a type-writing machine, the combination of a platen, a platen-shaft to which said platen is secured, a line-spacing ratchet-wheel, a crown gear-wheel carried by said 130

5 ratchet-wheel, a finger-wheel supported by said crown-wheel for rotating the platen and ratchet-wheel together, a gear-wheel connected to the platen-shaft, a regulating finger-wheel, and a gear-wheel loosely carried thereby and adapted to coöperate with the crown-gear and the gear which is connected to the platen-shaft to effect a movement of the platen relatively to the ratchet-wheel when 10 the regulating finger-wheel is turned.

15 3. In a type-writing machine, the combination of a platen, a line-spacing ratchet-wheel, a finger-wheel for rotating said platen and ratchet-wheel, a regulating finger-wheel, a bevel-gear connected to said ratchet-wheel, a bevel-gear connected to the platen, and a bevel-gear which is carried loosely by the regulating finger-wheel and coöperates with the other gears to effect a movement of the 20 platen and ratchet-wheel one with relation to the other when said regulating-wheel is rotated.

25 4. In a type-writing machine, the combination of a platen, a line-spacing ratchet-wheel, a finger-wheel carried by said ratchet-wheel for rotating said platen and ratchet-wheel together, a regulating finger-wheel, a toothed bevel crown-gear connected to the platen, and a toothed bevel-gear which is loosely carried 30 by the regulating finger-wheel and coöperates with the other gears to effect a movement of the platen and ratchet-wheel one with relation to the other when said regulating-wheel is rotated.

35 5. In a type-writing machine, the combination of a platen, a line-spacing ratchet-wheel, concentric gears one of which is connected to the ratchet-wheel and another to the platen, a regulating finger-wheel, and a gear-wheel 40 which revolves relatively to said finger-wheel and coöperates with the other gear-wheels to effect a movement of the platen relatively to the line-spacing ratchet-wheel.

45 6. In a type-writing machine, the combination of a platen, a line-spacing wheel, concentric gears, one of which is connected to the ratchet-wheel and another to the platen, a finger-wheel which is connected to one of said gears and is operative to rotate the platen and 50 gear-wheels together, a regulating finger-wheel, a gear-wheel which is carried thereby and coöperates with the other gears to effect a movement of the platen independently of the line-spacing wheel.

7. In a type-writing machine, the combination of a platen, a line-spacing wheel, a crown-gear carried thereby, a gear-wheel which is connected to the platen and which is concentric to the crown-gear, a finger-wheel which is connected to the crown-gear and which surrounds it and the gear which is concentric thereto, said finger-wheel being operative to rotate the platen and gear-wheels together, a regulating finger-wheel, and a gear which is carried thereby and coöperates with the other 60 gears to effect a movement of the platen independently of the line-spacing wheel.

75 8. In a type-writing machine, the combination of a platen, a line-spacing wheel, a bevel crown-gear carried thereby, a bevel gear-wheel which is connected to the platen and is concentric to the crown-gear, a finger-wheel which is connected to the crown-gear and which surrounds it and the gear which is concentric thereto, said finger-wheel being operative to rotate the platen and gear-wheels together, a regulating finger-wheel, a bevel-gear which is carried by said regulating finger-wheel and revolves relatively thereto and coöperates with the other gears to effect a 80 movement of the platen independently of the line-spacing wheel.

85 9. In a type-writing machine, the combination of a line-spacing wheel, a platen which is adapted to rotate independently of said line-spacing wheel, a regulating finger-wheel, intermediate gear connections between the regulating finger-wheel and the line-spacing wheel and between the regulating finger-wheel and the platen, and a spring which bears upon 90 said finger-wheel and maintains a close engagement between said gear connections.

95 10. In a type-writing machine, the combination of a platen, a line-spacing ratchet-wheel therefor, a train of differential bevel-gears 100 coöperating with the platen and ratchet-wheel and a finger-wheel which carries one of said bevel-gears and is adapted to move it bodily to operate the other gears to effect a movement of the platen and ratchet-wheel one with relation to the other.

Signed at Arlington, in the county of Bennington and State of Vermont, this 15th day of November, A. D. 1901.

WILLIAM C. FARNUM.
